(57) **CLAIM**

The ornamental design for a mobile security apparatus as shown and described herein.

DESCRIPTION

FIG. 1 illustrates a perspective view of a mobile security apparatus, according to a first embodiment.

FIG. 2 illustrates a front view of the mobile security apparatus, according to the first embodiment.

FIG. 3 illustrates a rear view of the mobile security apparatus, according to the first embodiment.

FIG. 4 illustrates a side view of the mobile security apparatus, according to the first embodiment.

FIG. 5 illustrates an opposite side view of the mobile security apparatus, according to the first embodiment.

FIG. 6 illustrates a top-down view of the mobile security apparatus, according to the first embodiment.

FIG. 7 illustrates a bottom-up view of the mobile security apparatus, according to the first embodiment.

FIG. 8 illustrates a perspective view of a mobile security apparatus, according to a second embodiment.

FIG. 9 illustrates a front view of the mobile security apparatus, according to the second embodiment.

FIG. 10 illustrates a rear view of the mobile security apparatus, according to the second embodiment.

FIG. 11 illustrates a side view of the mobile security apparatus, according to the second embodiment.

FIG. 12 illustrates an opposite side view of the mobile security apparatus, according to the second embodiment.

FIG. 13 illustrates a top-down view of the mobile security apparatus, according to the second embodiment; and,

FIG. 14 illustrates a bottom-up view of the mobile security apparatus, according to the second embodiment.

The broken lines shown in FIGS. 8 and 9 illustrate portions of the mobile security apparatus that form no part of the claimed design.
